UNITED STATES PATENT OFFICE.

WILLIAM B. FRANCIS, OF PRAGUE, OKLAHOMA.

PARTY-LINE CUT-OUT.

1,133,549.

Specification of Letters Patent. Patented Mar. 30, 1915.

Application filed June 14, 1913. Serial No. 773,640.

To all whom it may concern:

Be it known that I, WILLIAM B. FRANCIS, citizen of the United States, residing at Prague, in the county of Lincoln and State 5 of Oklahoma, have invented certain new and useful Improvements in Party-Line Cut-Outs, of which the following is a specification.

My invention relates to new and useful 10 improvements in switches for telephone systems and more particularly for use in telephones on party lines, my improved switch in fact constituting a party line cut-out switch and the object of my invention is to 15 provide a switch which is operable by the receiver hook and which renders it impossible, when two persons are using a line, for any other person on the line to overhear the conversation.

20 A further object of my invention is to so construct the switch and wire the instruments that when two parties on a line are using the line both ends of the line beyond their instruments are cut-off, thus preventing 25 any party on the line beyond either of them listening in on their conversation, and further so arranged that any party having an instrument between the parties using the line, who attempts to cut in, will immediately 30 cut-out one or the other of the two parties conversing and will therefore be unable to overhear their conversation. In this connection, it will be noted that the switches are so arranged that an intermediate party 35 cutting in in this manner will be unable to call any other than a second intermediate party. For these reasons, practically all intentional cutting in of third parties will be avoided. And a still further object of my 40 invention is to construct a receiver hook actuated switch capable of accomplishing the above objects and which will be composed of a few working parts and therefore simple in its operation, cheap to manufacture, and not liable to get out of order.

45 With these and other objects in view, my invention will be more fully described, illustrated in the accompanying drawings, and then specifically pointed out in the claims 50 which are attached to and form a part of this application.

In the drawings: Figure 1 is a top plan view of my improved switch, showing the same in place, the telephone box in which 55 the switch is mounted being shown in section and the switch being shown in normal

or inactive position; Fig. 2 is a similar view, showing the switch in one of its two active positions; Fig. 3 is a front elevation of the switch, showing it in the position shown in 60 Fig. 1; Fig. 4 is a fragmentary perspective view, showing the manner of mounting the receiver hook when used in connection with my improved switch; Fig. 5 is a sectional view on the line 5—5 of Fig. 4, further 65 showing the manner of mounting the hook; Fig. 6 is a plan view of a slotted plate through which the receiver hook extends and which controls the movement of said hook and consequently the operation of the 70 switch; Fig. 7 is a diagrammatic view, showing a number of instruments provided with my improved switch and included in a single party line.

Corresponding and like parts are referred 75 to in the following description and indicated in all the views of the drawings by the same reference characters.

In order to insure a clear understanding 80 of my invention I have illustrated the switch in place in a telephone box, conventionally shown at 10 and including a back wall 11 and end wall 12. A bracket 13, preferably formed of malleable iron, is secured by one 85 end to the back wall by screws or other fastening devices 14, being cut-away and bent to provide perforated lugs or ears for self-support and also for the support of the switch and receiver hook as will be more fully explained. This bracket 13 is provided 90 intermediate its length with a tongue 15 which is preferably up-bent slightly and which is perforated as shown at 16 to receive a rivet 17 or other pivotal fastening device, this rivet being passed upwardly through 95 the intermediate portion of a strip of sheet metal 18 and an extended end 19 of a U-shaped spring 20. The end portions of the strip 18 are bent inwardly across the side 100 edge portions of the extended end 19 of the spring and then upwardly in parallel spaced relation as shown at 21 after which they are bent outwardly and upwardly to provide spaced perforated ears 22. A metallic sleeve 105 23, preferably rectangular in section and provided with a rectangular longitudinal opening, is pivotally mounted between these ears by trunnions or other pivot devices 24 carried by the sleeve. The inner end of the arm 25 of the receiver hook 26 is passed through this sleeve 23 and the outer or hook end of said arm is passed through the end 110

- wall 12 of the box and through the slot 27 of a face plate 28 secured to the outer face of said end wall. This slot, as shown in Fig. 6, is T-shaped including an upper horizontal portion 29 and a central vertical portion 30. The opening in the end wall 12 of the box, for the passage of the arm, corresponds in shape to the slot of the plate and it will therefore be apparent that the receiver hook may be moved upwardly vertically under the action of the spring 20 when the receiver is removed from its hook and may then be swung manually to either end of the horizontal portion 29 of the slot.
- 15 In order to lock the receiver arm in either the forward or rear end of the portion 29 of the slot when moved to either position, I provide a leaf spring 31, the intermediate portion of which is secured to the upper edge of the horizontal portion of the slot by a screw or other fastening device as shown at 32 and the free ends of which are bowed downwardly and then upwardly to bear against the upper edge of the slot.
- 20 25 When the receiver arm is moved in either direction it engages one of the downwardly bowed portions of the spring and forces the same upward during its passage until it reaches the end of the slot when said bowed portion serves to lock the same against any return movement unless swung manually with sufficient strength to overcome the action of the spring.

The bracket carries upon either side of the receiver hook arm 25 a set of resilient contacts, the set at one side being indicated as a whole by the numeral 33 and that at the opposite side by the numeral 34. Each set includes the same number of contacts and 35 the contacts are similarly arranged, that is, the contacts of one set are symmetrically arranged with respect to the contacts of the other set. The contacts of the set 33 include a lower resilient contact 35 and upper contact 36 both secured to the bracket by fastening screws 37, these contacts being insulated from each other and from the bracket, as shown.

Resilient contacts 38 and 39 are secured 50 in parallel spaced relation adjacent the contacts 35 and 36 and in a plane somewhat above that of the contact 35, these contacts 38 and 39 being disposed edgeways as shown, for swinging movement toward and away 55 from the back wall of the box and being insulated from each other, from the contacts 35 and 36 and from the bracket 13. The contact 36 carries a downwardly directed pin 40 and a rearwardly directed pin 41, while the contact 38 carries a rearwardly directed pin 42.

The set of contacts 34 includes contacts 35' and 36' corresponding to the contacts 35 and 36, and contacts 38' and 39' corresponding to the contacts 38 and 39, the

contact 36' being provided with pins 40' and 41' corresponding to the pins 40 and 41 and the contact 38' with a pin 42' corresponding to the pin 42.

The receiver hook arm 25 is provided intermediate its length with forwardly and rearwardly directed cross arms 43 which are either formed of insulation or suitably insulated from the receiver arm and which seat in spring forks 44 formed in the extended ends of the contacts 36 and 36'.

By referring to Fig. 3 of the drawings, it will be seen that because of this connection between the receiver hook arm 25 and the contacts 36 and 36', the latter will be held with their pins 40 and 40' in engagement with the contacts 35 and 35' respectively, when the receiver hook is held in depressed position by the weight of the receiver. It will further be apparent that when the receiver hook is moved to the upper end of the vertical portion 30 of the slot, the contacts 36 and 36' will move upwardly to break the circuits between the contacts 35-35' and 36-36'. When in this upper position, the contacts 36 and 36' lie in the same horizontal plane with the contacts 38, 39, 38' and 39'. It will therefore be apparent that if the receiver hook is moved rearwardly, the pin 41 of the contact 36 will engage the contact 38 and force the same rearwardly until its pin 42 engages the contact 39. In like manner, if the receiver hook is swung forwardly, the contact 36' will be swung forwardly until its pin 41' engages the contact 38' swinging the same forwardly to bring its pin 42' into engagement with the contact 39'.

Having thus described the mechanical structure of one of my improved switches I will now explain the manner of wiring the same when they are employed with the usual telephones in a party line system. These party line systems are usually of one of two types, one being known as the ground return system and the other as the metallic return system. It will be apparent that the wiring will differ slightly according to which system is employed but as both are well known I have illustrated the wiring diagrammatically for the ground return system alone.

Although I have illustrated but three instruments A, B and C in the line, it will of course be understood that any number of instruments desired may be employed. In the ground return system the line is made up of a plurality of sections each including a conductor wire 45 which, as shown, electrically connects the contact 36 of one instrument with the contact 36' of the adjacent instrument. A wire 46 in the system connects the contacts 35' and 35, while a wire 47 connects the contacts 38 and 38'. A wire 48 connects the contacts 39 and 39'.

A magneto bell 49 is located at each in-

strument and connected by one terminal to the ground as shown at 50 and at its other terminal by a conductor wire 51 with the contact 35' of its instrument. A conductor 5 wire 52 leads from the contact 39' to the transmitter 53 and a wire 54 leads from the transmitter to a battery 55. A wire 56 leads from this battery to the primary winding 57 of an induction coil 58 and a wire 59 leads from said winding to the contact 38'. A wire 60 also leads from the contact 38' to the secondary winding 61 of the induction coil 58 and a wire 62 leads from said secondary coil to the receiver 63 from which a 15 wire 64 leads to the ground.

In operation, assuming that the receiver hooks of all instruments are in place and the contacts 36 and 36' of all instruments therefore in engagement with the contacts 20 35 and 35' of their respective instruments, it will be apparent that any ringing current 25 passing over the line will pass from one wire 45 to the contact 36' of one instrument, through said contact to the contact 35' of the same instrument, through the wire 46 to the contact 35, through said contact to the contact 36, through the next section or wire 45 to the next instrument in the line and so on throughout the entire line. At each instrument 30 the current will also pass through the wire 51 to the magneto bell 49 and so to the ground ringing the bell. As soon as the subscriber called raises his receiver from its hook, the hook is raised by the spring 20 35 and the circuit broken between the contacts 35—35' and 36—36' of his instrument which opens the main line at his instrument. If the subscriber then moves the receiver hook rearwardly he will bring the contacts 36, 38 40 and 39 into engagement and his instrument will then be in circuit with all instruments along the line in one direction. If, on the other hand, he swings his receiver hook forwardly, the contacts 36', 38' and 39' will be 45 in engagement and his instrument will be connected with the line in the other direction. When called therefore he may swing the receiver hook first in one direction and then in the other to determine from which 50 direction he is being called. In the meantime, the party calling has also raised his receiver hook and swung it in the proper direction. When the parties have thus connected their instruments it will be apparent 55 that all instruments upon either side of the two parties are cut out and that if any instrument between the parties cuts in one of the parties will be cut out. Furthermore, any instrument cutting in between the 60 parties, when the instruments are connected, can get connection only with any intermediate instrument.

The remainder of the wiring and its operation in the ordinary employment of a 65 party line system is conventional and will

therefore be readily understood and no description of the same is therefore necessary. It will of course be understood that I do not wish in any way to limit myself to the specific details of construction illustrated 70 in the drawings and described in the specification as various minor changes, within the scope of the appended claims, may be made at any time without in the slightest degree departing from the spirit of my invention. 75

Having thus described the invention, what is claimed as new is:

1. In a party line cut-out, a group of contacts adapted for electrical connection to a telephone instrument and a line, a second similar group of contacts adapted for electrical connection to the same instrument and line, and a telephone hook pivoted for vertical movement and subsequent horizontal movement controlling the closing of circuits through said contacts. 80

2. In a party line cut-out, a group of contacts adapted for electrical connection to a telephone instrument and a line, a second similar group of contacts adapted for electrical connection to the same instrument and line, and a telephone hook pivoted for vertical movement and subsequent horizontal movement controlling the closing of circuits through said contacts, the hook in lowered position closing a circuit through certain contacts of each group and in raised position being movable in one direction to close circuits through the contacts of one 90 group and in the opposite direction to close circuits through the contacts of the other group. 95

3. In a party line cut-out, a group of contacts adapted for electrical connection to a telephone instrument and a line, a second similar group of contacts adapted for electrical connection to the same instrument and line, and a telephone hook pivoted for vertical movement and subsequent horizontal movement controlling the closing of circuits through said contacts, the hook in lowered position closing a circuit through certain contacts of each group and in raised position being movable in one direction to close 105 circuits through the contacts of one group and in the opposite direction to close circuits through the contacts of the other group, said hook when in raised position opening the circuit which it closes when 110 lowered. 115

4. In a party line cut-out, a group of contacts adapted for electrical connection to a telephone instrument and a line, a second similar group of contacts adapted for electrical connection to the same instrument and line, and a telephone hook pivoted for vertical movement and subsequent horizontal movement controlling the closing of circuits through said contacts, the hook in lowered 125 130

position closing a circuit through certain contacts of each group and in raised position being movable in one direction to close circuits through the contacts of one group 5 and in the opposite direction to close circuits through the contacts of the other group, said hook when in raised position opening the circuit which it closes when lowered, and means for automatically securing 10 the receiver hook in either of its raised positions.

5. In a party line cut-out, a pivoted receiver hook, a set of spaced contacts supported at each side of the hook, electrical 15 connection between each contact of one group and the corresponding contact of the other group, a divided main line, and means connected to the ends of the main line and operable by the receiver hook for establishing 20 connection between one set of said contacts and one end of the line or between the other set of said contacts and the other end of the line.

6. In a party line cut-out, a receiver hook 25 mounted for vertical and horizontal movement, a set of spaced contacts supported at each side of the hook, electrical connection between each contact of one group and the corresponding contact of the other group, 30 a divided main line, and means connected to the ends of the main line and operable by the receiver hook for establishing connection between one set of said contacts and one end of the line or between the other set 35 of said contacts and the other end of the line, said means being operable by first raising the hook and then swinging the same horizontally in one direction or the other.

7. In a party line cut-out, a pivoted receiver hook mounted for swinging movement in a vertical plane and also in a horizontal plane, a plurality of resilient contacts positioned at one side of the hook, a plurality of resilient contacts positioned at 45 the other side of the hook, electrical connection between each contact of the first and the corresponding contact of the second, the contacts of both being adapted for connection with a line and with a telephone 50 instrument, and means operable by swinging the receiver hook in one direction or the other for closing the circuits through one group of contacts or the other.

8. In party line cut-outs, a divided main 55 line, a group of contacts adapted for electrical connection between the telephone instrument and one side of the main line, a similar group of contacts adapted for electrical connection between the same instrument and the other side of the main line, electrical connection between each contact of one group and a contact of the other group, a receiver hook, and means operable by movement of the receiver hook for clos-

ing the circuit through either set of contacts. 65

9. In party line cut-outs, the combination with a divided line, a telephone instrument and a vertically movable receiver hook, of means operated by the hook when in lowered position for connecting the line sections, and means operable by movement of the hook after raising the same for connecting the instrument to either side of the line. 70

10. In party line cut-outs, a telephone box 75 provided with a T-shaped slot, a receiver hook extending through the slot and mounted for swinging movement in both a vertical and a horizontal plane, a divided main line, means operable by the lowering of the hook 80 for connecting the sides of the line, means operable by the raising of the hook for opening the line, and means operable by the subsequent horizontal movement of the hook for connecting its telephone with 85 either side of the line.

11. In party line cut-outs, a telephone box provided with a T-shaped slot, a receiver hook extending through the slot and mounted for swinging movement in both a vertical 90 and a horizontal plane, a divided main line, means operable by the lowering of the hook for connecting the sides of the line, means operable by the raising of the hook for opening the line, and means operable by the 95 subsequent horizontal movement of the hook for connecting its telephone with either side of the line, said means being operable by the swinging of the receiver hook forwardly or rearwardly. 100

12. In party line cut-outs, a telephone box provided with a T-shaped slot, a receiver hook extending through the slot and mounted for swinging movement in both a vertical and a horizontal plane, a divided main line, 105 means operable by the lowering of the hook for connecting the sides of the line, means operable by the raising of the hook for opening the line, means operable by the subsequent horizontal movement of the hook 110 for connecting its telephone with either side of the line, said means being operable by the swinging of the receiver hook forwardly or rearwardly, and means for locking the hook in either of said positions. 115

13. In party line cut-outs, a telephone box provided with a T-shaped slot, a receiver hook extending through the slot and mounted for swinging movement in both a vertical and a horizontal plane, a divided main line, 120 means operable by the lowering of the hook for connecting the sides of the line, means operable by the raising of the hook for opening the line, and means operable by the subsequent horizontal movement of the hook 125 for connecting its telephone with either side of the line, said means being operable by the swinging of the receiver hook forwardly or

rearwardly, and means for locking the hook in either of said positions, said means comprising a leaf spring secured centrally to the central portion of the horizontal part of the 5 T-shaped slot and having bowed end portions projecting in the path of the receiver hook.

14. In a party line cut-out, the combination with a divided main line and a telephone instrument including a receiver hook, bell, transmitter and receiver, of contact members electrically connected one to each side of the line and operatively connected to the receiver hook for movement therewith, means co-acting with said members to close a circuit through the line and bell upon depression of the receiver hook, and means co-acting with said contact members to operatively connect the receiver and transmitter 20 to either side of the line by movement of the receiver hook in one direction or the other when raised.

15. In a party line cut-out, the combination with a divided main line and a telephone instrument including a receiver hook, bell, transmitter and receiver, of contact members electrically connected one to each side of the line and operatively connected to the receiver hook for movement therewith, means co-acting with said members to close a circuit through the line and bell upon depression of the receiver hook, and means co-acting with said contact members to operatively connect the receiver and transmitter 30 to either side of the line by movement of the receiver hook in one direction or the other when raised, said means including a plurality of spaced contacts electrically connected with the receiver and transmitter and 35 in position for engagement by one of the contact members operatively connected to the receiver hook when the receiver hook is swung in one direction, and a second set of similar contact members similarly connected and in position to be engaged by the other contact member operatively connected to the receiver hook when the receiver hook is swung in the opposite direction.

16. In a party line cut-out, the combination with a divided main line and a telephone instrument including a receiver and transmitter, of a receiver hook mounted for movement in both a horizontal and a vertical plane, means operated by the movement 55 of the receiver hook in one direction for establishing connection through the divided line, means operable by the receiver hook in another direction for breaking said connection, means operable by the receiver hook 60 in another direction for establishing connection between one side of the line and the receiver and transmitter, and means operable by the movement of the receiver hook

in still another direction for establishing connection between the other side of the line 65 and the receiver and transmitter.

17. In a party line cut-out, the combination with a divided main line and a telephone instrument including a receiver and transmitter, of a receiver hook mounted for movement in both a horizontal and a vertical plane, means operable by the movement of the receiver hook in one direction for establishing connection through the divided line, means operable by the receiver hook in another direction for breaking said connection, means operable by the receiver hook in another direction for establishing connection between one side of the line and the receiver and transmitter, means operable by the movement of the receiver hook in still another direction for establishing connection between the other side of the line and the receiver and transmitter, and means for automatically holding the receiver hook 80 when moved in either of the two last named directions.

18. A party line cut-out including a box provided with a T-shaped slot, a receiver hook pivoted for movement in a vertical or 90 a horizontal plane extending through said slot and movable to all parts thereof, a bracket supporting the inner end of said hook, means for normally holding the hook in elevated position, means for automatically 95 securing the hook when swung horizontally, resilient contacts carried by the bracket and operatively connected to the hook one upon either side thereof, a divided line, one side being connected to one contact and one side 100 to the other, a pair of contacts mounted one adjacent each of the first contacts and electrically connected to each other and to a bell, the first contacts being adapted to engage the second contacts upon depression of 105 the receiver hook, and a pair of spaced contacts insulated from each other and from the other contacts located at one side of each of the first contacts, the contacts of each pair being adapted to be forced into engagement 110 with each other and with the adjacent of the first mentioned contacts upon swinging of the receiver hook toward said pair, electrical connection between each contact of one pair and the corresponding contact of the other, 115 and electrical connection between one contact of one pair and a receiver and between the other contact of said pair and a transmitter.

In testimony whereof I affix my signature 120 in presence of two witnesses.
